DESIGN FOR A CANDLESTICK LIGHTING FIXTURE

Sylvester A. Baker, San Francisco, Calif.

Application February 5, 1936, Serial No. 60,991

Term of patent 7 years

To all whom it may concern:

Be it known that I, Sylvester A. Baker, a citizen of the United States of America, residing at San Francisco, in the county of San Francisco and State of California, have invented a new, original, and ornamental Design for Candlestick Lighting Fixtures, of which the following is a specification, reference being had to the accompanying drawing, forming a part thereof.

The figure is a front elevation of a candlestick lighting fixture, showing my new design.

The opposite side is substantially the same as the side shown.

I claim:

The ornamental design for a candlestick lighting fixture substantially as shown and described.

SYLVESTER A. BAKER.
